NEAL LARKIN ANDERSON, OF WINSTON-SALEM, NORTH CAROLINA.

TYPE-WRITER CARRIAGE-RETURN MECHANISM.

1,187,124.

Specification of Letters Patent. Patented June 13, 1916.

Application filed April 10, 1915. Serial No. 20,379.

To all whom it may concern:

Be it known that I, NEAL L. ANDERSON, a citizen of the United States, residing at Winston-Salem, county of Forsyth, and 5 State of North Carolina, have invented certain new and useful Improvements in Type-Writer Carriage-Return Mechanism; and I do hereby declare the following to be a full, clear, and exact description of the invention, 10 such as will enable others skilled in the art to which it appertains to make and use the same.

This invention relates to carriage return mechanism for typewriters and similar machines and more particularly to return mechanisms in which a motor is employed for effecting the return of the carriage at the end of the line of print.

The object of the invention is to provide 20 a return mechanism of this character which is simple in construction, which may be operated by unskilled persons, which is reliable and efficient in its operation, with which the speed of the return movement is 25 automatically regulated, with which a return movement of any length is effected without excessive jarring of the parts of the mechanism, and which is controlled by a single manually-operated key lever regardless of the distance through which the 30 carriage is to be returned.

A fundamental characteristic of the invention is embodied in the mechanism for automatically controlling the motor by 35 which the return of the carriage is effected. Preferably, an electric motor is employed and the automatic control thereof is effected by introducing and withdrawing resistance from the circuit of the motor. The 40 automatic controlling devices are such that when the operating lever is actuated to close the circuit of the motor, the latter is caused to operate with sufficiently high torque to insure movement of the carriage with the 45 desired rapidity, and toward the end of the movement of the carriage, resistance is automatically introduced into the circuit of the motor so as to diminish its torque in order to avoid excessive jar at the end of 50 the movement of the carriage but insure that the carriage will be positively moved to the end of its travel. The means for introducing the resistance into the motor circuit is arranged to be governed automatically by the extent to which the carriage 55 was moved prior to the actuation of

the return mechanism; if the carriage was moved to the limit of its travel or practically so, the maximum resistance is introduced into the motor circuit near the conclusion of the return movement, and movement of the carriage to an extent less than the maximum results in the introduction of less than the whole amount of resistance into the motor circuit near the conclusion 60 of the return movement of the carriage. With such an automatic controlling mechanism, the closure of the motor circuit results in starting the motor with relatively high torque so that the return movement of 70 the carriage is effected rapidly and a substantial amount of momentum developed. As the carriage nears the end of its return movement, the resistance is introduced into the motor circuit and the torque of the 75 motor is correspondingly reduced. The momentum previously developed may be sufficient to carry the carriage to the end of its return movement without excessive jar after the torque of the motor is thus reduced, but irrespective of this, the motor continues in operation and if necessary, completes the return movement of the carriage.

The automatic regulation of the motor circuit arranged in this manner possesses the further advantage that it facilitates providing for the return of the carriage through short distances without excessive jar and actuation of the return mechanism with a single lever irrespective of the distance through which the carriage is to be returned. When the carriage is moved but a short distance, as when the typewriting machine is used to write a short line, it is undesirable to have the motor, in effecting the return movement, develop the same initial torque as is provided for in returning the carriage through the whole range of its movement. In accordance with the invention, provision is 95 made whereby when returning the carriage after the writing of short lines, resistance is automatically introduced into the motor circuit so that such return movement will be effected with the motor developing a reduced torque. However, the resistance introduced into the motor circuit when returning the carriage through short distances is less than the maximum amount introduced at the end of a return movement of 100 the carriage through its full range, for the reason that if the full amount of resistance

were introduced when returning the carriage through a short distance, the starting torque of the motor would be insufficient to insure a prompt and positive return of the carriage. By reason of the provision of such automatic controlling devices for regulating the current flow in the motor circuit both when returning the carriage through its full range and when returning it through short distances, a single operating lever suffices for the actuation of the mechanism under all conditions. Furthermore, the mechanism may be greatly simplified, especially in the elimination of numerous latches and triggers, so that it may be readily operated by unskilled persons and may be relied on to operate effectively under all conditions without excessive jar.

The features of the invention above referred to and other features of substantial value and importance will be better understood by reference to the following description taken in connection with the accompanying drawings illustrating one form in which the invention may be embodied.

In these drawings, Figure 1 is a front view of a typewriter having a return mechanism constructed in accordance with the invention attached thereto; Fig. 2 is a top view of a portion of the typewriter; Fig. 3 is a central longitudinal section through the return mechanism; Fig. 4 is a top view of the return mechanism; Fig. 5 is a transverse section on line 5—5 of Fig. 3; Fig. 6 is a diagrammatic view showing the electrical connections; Fig. 7 is a sectional elevation showing the key-lever and the switch operated thereby; Fig. 8 is a sectional elevation showing the rheostat; Figs. 9 and 11 are views, partly diagrammatic, showing the operating contacts and the electrical connections thereto; and Fig. 10 is a top view of the contacts.

Referring to these drawings, A indicates a typewriter having the usual reciprocating paper-carriage B which is provided with an ordinary rotary platen C by means of which the paper is supported and spaced for successive lines of printing. At the right of the carriage B is the usual pivoted and spring-retracted lever D which is grasped in order to return the carriage by hand and at the same time effect the line spacing. The return of the carriage is effected by a cord or tape E which is connected to and wound on a winding drum P mounted on the shaft F of an electric motor. This tape passes over a pulley G mounted on the frame of the machine and its end is connected to a pin H on a reciprocating bar I. This bar is guided in its movements by projections i and i' mounted on the frame of the carriage and the end of the bar is connected to a crank K which is secured to the shaft of the lever D.

For the purpose of returning the carriage when the end of the desired type line has been reached, I employ the automatic carriage-return mechanism L shown at the right in Fig. 1 and comprising a casing M within which the motor and certain of the parts actuated thereby are inclosed. The shaft F of the motor projects through the end of the casing M and carries the drum P on which the tape E is wound. Rotation of the shaft of the motor in a counter-clockwise direction revolves the drum so as to wind the tape thereon to return the carriage and at the same time effect the line spacing by means of the devices above described.

The automatic regulation of the speed of the return movement of the carriage will now be described. Referring particularly to Figs. 3, 4 and 5, the shaft F of the motor has a worm 7 thereon which meshes with a worm-wheel 8 mounted upon the upper end of a shaft 9, which is adapted to rotate in bearings formed in the base of the casing M and in a bracket 10 projecting laterally from a wall of the casing. On this shaft 9 is a sleeve 11 of insulating material and a metallic collar 12 surrounds a portion of this insulating sleeve 11 and is adapted to rotate loosely thereon. The lower end of the collar 12 fits within a piece of molded insulated material 13 mounted upon the base of the casing M and shaped to form a spool upon which the resistance wire 40 hereinafter referred to is wound. The insulating material 13 constitutes a base-plate upon which a plurality of contacts 14, 15, 16, 17 and 18 are mounted. These contacts are adapted to be engaged by a switch-arm 19 projecting from the collar 12. In addition to the contacts 14 to 18 are two other contacts 20 and 21 of arc shape, the several contacts 14, 15, 16, 17, 18, 20 and 21 being arranged in the arc of a circle as shown. The contacts 20 and 21 are adapted to be engaged by an arm 22 which projects laterally from a collar 23 mounted upon the shaft 9 so as to turn therewith but insulated from the shaft as shown in Fig. 5. Electrical connection to the collar 23 is made by a spring-arm 39 mounted at one end upon a stud on the insulating base 13 and having its opposite end bearing against the collar 23. The collar 23 has a stud or screw 24 projecting laterally therefrom and adapted to engage a stud 25 rising from the disk at the upper end of the collar 12 so that when the collar 23 and its screw 24 are turned with shaft 9, the screw 24 engages stud 25 and turns the latter and the collar 12 so as to carry the contact arm 19, which is fixed to the collar 12, around over the contacts 14, 15, 16, 17 and 18. Such movement of the collar 12 is effected against the tension of a spring 26 connected at one end to a stud on the collar 12 and at the other end to a screw on

the insulating base 13. When the collar 12 is released as hereinafter described and retracted by the spring 26, its backward movement is arrested by a stud or contact 27 rising from the insulating base 13 and so positioned that it is engaged by the arm 19 when the latter rests upon the contact 14.

After the arm 19 has been moved against the tension of spring 26 by the screw 24 on collar 23, it is held in the position to which it has been moved when the collar 23 is turned back. For this purpose, the edge of the disk at the upper end of the collar 12 is provided with ratchet teeth, as shown in Fig. 4, adapted to be engaged by the end of a pivoted lever 28 whose end is pressed toward the teeth by a spring 49 mounted upon the insulating base 13. The opposite end of the lever 28 is adapted to coact with a cam 50 (Figs. 4 and 7) mounted upon the operating lever 31, whose end projects forward to a convenient position and carries a key 32. The lever 31 is pivotally mounted upon a standard 33 rising from the base of the casing M and is provided with an offset 34 (Fig. 5) adapted to engage a stud 35 projecting upwardly through an opening in the base of the casing from a spring-arm 87 (Fig. 7). This arm is mounted at one end 30 upon an insulating block 36 and at its opposite end it is adapted to engage a contact Y which is similarly mounted upon an insulating block secured to the under side of the base of the casing M.

35 The electrical connections will be best understood by reference to Figs. 6, 9 and 11, wherein the motor N and the parts connected thereto are shown diagrammatically. Current is supplied by wires w, w' which 40 may lead from a plug adapted to be inserted in a socket of the usual construction. The wire w leads to one side of the series motor N, and from the other side of the motor, connection is made to the spring-arm 87 45 which is actuated by the key-lever 31 as above described. The arm 87 and its coöperating contact Y are shunted by a condenser T. From the contact Y a wire W leads to the arm R' of a rheostat R, which 50 may be adjusted to adapt the apparatus for use upon circuits of different voltages. This rheostat and its controlling arm R' are mounted upon the under side of the base of the motor casing M as is shown in Fig. 8. 55 From the other side of the rheostat, a wire 38 leads to the contact 37, from which electrical connection is made to the collar upon which the switch-arm 22 is mounted by the spring-arm 39 shown in Fig. 4. The other 60 side of the circuit is connected by the wire w' to the contact 20 as shown and by a wire 41 to the stud on the base 13 to which the spring 26 is connected. The resistance wire 40, which is wound upon the insulating base 13, is connected at one end to the contact 21

and at the other end to the contact 18. At a plurality of intermediate points on the resistance wire 40, connections are made to the contacts 17, 16, 15 and 14 and to the stud 27, as shown diagrammatically in Fig. 6.

70 The operation of the parts thus constructed and arranged will now be described.

As the carriage of the typewriting machine moves from right to left during the writing operation, the armature of the motor and its shaft F are turned in their bearings by the tape E which is drawn off from the drum P. This results in turning the shaft 9 through the worm gearing 7 and 8 and the contact-arm 22 is moved around 80 in a counter-clockwise direction over the contacts 21 and 20. If a line of the maximum length be written so that the carriage moves through its full range, the arm 22 moves from the position shown in Figs. 6 and 11 85 at one end of the contact 21 over that contact and the contact 20 to the distant end of the contact 20. During this movement of the arm 22, the screw 24 on the collar 23 of the arm 22 engages the stud 25 on the loose collar 12 and turns that collar and the arm 19 thereon, thus causing the arm 19 to move over the contacts 14, 15, 16, 17 and 18. If it be desired to return the carriage to the initial position, the key 32 is 90 depressed. This carries cam 50 away from lever 28, the latter is moved by spring 49 to engage the teeth on the edge of the disk on sleeve 12, and arm 19 is thus held in the position to which it was moved. The depression of key 32 depresses the stud 35 on the switch-arm 87 so as to close the motor circuit at the contact Y. Current then flows from the wire w through the motor N to the switch-arm 87, contact Y, wire W, 105 rheostat R, wire 38, stud 37, arm 39, collar 23 and arm 22 to contact 20 and then out through the wire w'. The full current is thus admitted to the motor and the latter starts in operation at its full torque, thus 110 turning the shaft F and drum P and winding up the tape E on the drum. As the shaft F rotates, it causes rotation of shaft 9 and the arm 22 thereon is carried around over the contact 20 and upon the contact 115 21. The arm 22 reaches the contact 21 when the carriage nears the end of its return movement and the passage of the arm 22 from the contact 20 to the contact 21 introduces the resistance 40 into the motor circuit, so that the flow of current through the motor and consequently the torque of the motor, are considerably diminished. It will be seen that after the arm 22 moves upon the contact 21, the current flow will 125 be from the arm 22 to the contact 21, then through the resistance 40 to the contact 18, arm 19, sleeve 12, spring 26 and wire 41 to the wire w'. The conclusion of the return movement of the carriage will thus be 130

effected with the resistance 40 in the motor circuit. During the preceding movement of the carriage effected prior to the introduction of the resistance, an amount of momentum may have been developed sufficient to carry the carriage to the end of the range of its return movement, but if such an amount of momentum had not been developed, the operation of the motor with the reduced torque would serve to carry the carriage promptly and positively to its final position. After the carriage reaches its final position, the key-lever 32 is released and is returned to its normal position by the spring-arm 87. The upward movement of the key-lever effected thus, carries the cam 50 into engagement with the end of the lever 28, thus turning the lever so as to withdraw its end from coaction with the teeth of the ratchet on the sleeve 12. The sleeve, being thus released, is retracted by the spring 26 so that the arm 22 is moved around over the contacts from the contact 18 to the contact 14, where its movement is arrested by the stud 27.

If the typewriter were operated to print a short line, so short that the movement of the carriage caused only a slight movement of the arm 22 over the surface of the contact 21 and no movement of arm 19, the closure of the motor circuit by depression of the key-lever 32 would be effected with a portion of the resistance 40 included in the motor circuit so that the motor would operate to return the carriage with its torque substantially reduced. The path of the current would then be from the arm 22 to contact 21, then through the first section of the resistance 40, then by the connecting wire to the stud 27, then to arm 19 in contact with stud 27, to sleeve 12, spring 26 and wire 41 to wire w' .

If the typewriter were operated to write a line of greater length, the movement of the arm 22 corresponding to the movement of the typewriter carriage would carry the screw 24 into engagement with the stud 25 so as to move the arm 19 from the contact 14 to one of the contacts 15, 16, 17 or 18 depending on the length of the line written. Then the closure of the motor circuit by depression of the key 32 to effect return of the carriage would result in starting the motor with high torque, the current flowing from the arm 22 to the contact 20 and out through the wire w' . The return movement of the carriage thus effected would cause movement of arm 22 and when the arm passed from the contact 20 to the contact 21, resistance would be inserted in the motor circuit; this resistance, however, would be less than the whole amount of the resistance 40 by an amount depending upon which one of the contacts 14 to 18 was engaged by the arm 19 at the conclusion of the advance

movement of the carriage. Thus, if a line of substantially the full length be written, the advance movement of the carriage is accompanied by movement of arm 22 from contact 21 to contact 20 and arm 19 from contact 14 to contact 18; then the return movement would be effected first with no resistance in the motor circuit and then with all the resistance 40 in circuit. If a line of less length were written, the return of the carriage would be effected in the same manner except that in writing the shorter line, the arm 19 would not be moved all the way around to the contact 18 and therefore a less amount of resistance would be cut into the motor circuit toward the end of the return movement. If a very short line were written, the arm 19 would not be moved at all and the arm 22 would not move off the contact 21 during the advance movement; therefore, resistance would be included in the motor circuit and the torque of the motor proportionately diminished at the start and throughout the whole of the short return movement of the carriage, but this resistance would not be of such large amount as would cut down the power of the motor to an undesirable extent. If it were attempted to return the carriage through a short distance with such an amount of resistance in circuit as is desirable during the corresponding portion of the full return movement of the carriage, it would be found that the starting torque of the motor would be insufficient to effect a prompt and positive return of the carriage.

The length of the contacts 20 and 21 may be varied as desired; in practice, I have found it desirable to have the contact 21 of such length that the carriage moves through about one-third of its range of movement before the arm 22 passes from the contact 21 to the contact 20.

In the drawings, I have shown a cord tension regulator 29 adapted to close the motor circuit at 30, its lines being in shunt with the main circuit at the points K and Z. The function of this device is fully described in my Patent No. 953,938, dated April 5, 1910, so that detailed description thereof here is unnecessary.

It will thus be seen that the invention involves the provision of means for automatically controlling the effective power of the motor by the motor itself; that this includes means whereby the motor causes a reduction in the torque developed by the motor toward the end of the return movement of the carriage effected by the motor; and that the reduction in the power of the motor toward the end of the return movement is proportional to the extent of the advance movement of the carriage. As the carriage advances, it sets the contacts of the resistance so as to determine the amount of

resistance which shall be included in the motor circuit when the return movement of the carriage nears the end thereof. Furthermore, it will be seen that when the carriage is returned through short distances, special conditions prevail for insuring proper movement of the carriage; resistance is introduced into the motor circuit to cut down the torque of the motor but the amount of this resistance is only such as will prevent an undesirable jar at the end of the movement of the carriage.

While I have illustrated and described the embodiment of my invention which I prefer to employ, I realize that various other constructions may be employed to attain the objects of the present invention. I wish it understood, therefore, that I consider the invention to be independent of the particular construction illustrated except where elements of construction are specified in the appended claims and that I aim to cover modifications of the construction described by the terms employed in the claims.

25 What I claim is:

1. In a carriage-return mechanism, the combination of a typewriter having a carriage, a motor, means operated by the motor for returning the carriage and means operated automatically by the motor for reducing but not wholly discontinuing the effective power of the motor during the return movement of the carriage; substantially as described.

30 2. In a carriage-return mechanism, the combination of a typewriter having a carriage, a motor, means operated by the motor for returning the carriage and means operated automatically by the motor for reducing the effective power of the motor near the end of the return movement of the carriage to permit the carriage to be carried to the end of its movement by momentum, the motor being continued in operation to insure full return of the carriage; substantially as described.

35 3. In a carriage-return mechanism, the combination of a typewriter having a carriage, a motor, means operated by the motor for returning the carriage and means operated automatically by the motor for reducing the effective power of the motor during the return movement of the carriage an amount dependent upon the extent of the advance movement of the carriage; substantially as described.

40 4. In a carriage-return mechanism, the combination of a typewriter having a carriage, a motor, means operated by the motor for returning the carriage and means operated automatically by the motor for reducing the effective power of the motor during the return movement of the carriage, the motor being continued in operation until the movement of the carriage has been com-

pleted to insure complete return of the carriage; substantially as described.

5. In a carriage-return mechanism, the combination of a typewriter having a carriage, a motor, means operated by the motor for returning the carriage, means for automatically reducing the effective power of the motor during the latter portion of a full return movement of the carriage, and means for automatically reducing the effective power of the motor when returning the carriage through short distances, the amount of said reduction during short movements being different from the amount of the reduction during the corresponding portion of a full return movement; substantially as described.

6. In a carriage-return mechanism the combination of a typewriter having a carriage, a motor, means operated by the motor for returning the carriage, means for automatically reducing the effective power of the motor a relatively small amount when returning the carriage short distances and means for automatically reducing the effective power of the motor a relatively large amount when returning the carriage through the latter portion of a full return movement; substantially as described.

7. In a carriage-return mechanism for typewriters, the combination of a motor, means operated thereby for returning the carriage, means for automatically reducing the effective power of the motor a predetermined amount when returning the carriage through a predetermined portion of its range of movement at the end of that range of movement and means for automatically reducing the effective power of the motor a greater amount when moving the carriage through said predetermined portion of its movement at the end of a full return movement of the carriage; substantially as described.

8. In a carriage-return mechanism for typewriters, the combination of a motor, means operated thereby for returning the carriage, means for automatically reducing the effective power of the motor during the latter portion of the return movement of the carriage an amount dependent upon the extent of the advance movement of the carriage, and means for reducing the effective power of the motor when returning the carriage after a short advance movement an amount less than the amount to which the effective power of the motor is reduced when returning the carriage through the same range at the end of a full return movement of the carriage; substantially as described.

9. In a carriage-return mechanism for typewriters, the combination of a motor, means operated thereby for returning the carriage, a rheostat controlling the motor

- circuit, and means for operating the rheostat automatically to reduce but not wholly dis-
5 continue the effective power of the motor during the return movement of the carriage effected by the motor; substantially as de-
scribed.
10. In a carriage-return mechanism for typewriters, the combination of a motor, means operated thereby for returning the carriage, a rheostat controlling the resist-
10 ance of the motor circuit and means oper-
ated automatically by the motor for actuating the rheostat during the return move-
15 ment of the carriage, the operation of the rheostat being dependent upon the extent
15 of the advance movement of the carriage; substantially as described.
11. In a carriage-return mechanism, the combination of a typewriter having a car-
20 riage, a motor, means operated by the motor for returning the carriage, means for automatically introducing resistance into the motor circuit during the latter portion of a return movement of the carriage and for
25 varying the amount of said resistance in accordance with the extent of the advance movement of the carriage; substantially as described.
12. In a carriage-return mechanism, the combination of a typewriter having a car-
30 riage, a motor, means operated by the motor for returning the carriage, a member positioned automatically during the advance movement of the carriage for reducing the
35 effective power of the motor during a portion of the return movement effected by the carriage and a second member positioned automatically during the advance movement of the carriage for determining the amount
40 of said reduction; substantially as described.
13. In a carriage-return mechanism, the combination of a typewriter having a car-
45 riage, a motor, means operated by the motor for returning the carriage, a member positioned automatically during the advance movement of the carriage for causing res-
50istance to be introduced into the motor circuit during a portion of the return move-
55 ment of the carriage and a second member positioned automatically during the advance movement of the carriage for determining the amount of said resistance; substantially as described.
14. In a carriage-return mechanism, the combination of a typewriter having a car-
55 riage, a motor for returning the carriage, a variable resistance for regulating the motor circuit, a contact member operated in ac-
60 cordance with the movement of the carriage to control the introduction of resistance into the motor circuit, a second contact member for controlling the amount of said resist-
65 ance to be connected in the motor circuit and means for actuating the second contact member automatically during the latter part
70 of the advance movement of the carriage; substantially as described.
15. In a carriage-return mechanism, the combination of a typewriter having a car-
75 riage, a motor for returning the carriage, a variable resistance for regulating the motor circuit, a contact member operated in accordance with the movement of the carriage to control the introduction of resistance into the motor circuit, a second contact member for controlling the amount of said resistance to be connected in the motor circuit, means for actuating the second contact member automatically during the latter part of the advance movement of the carriage, and means for retaining the second contact member in the position to which it was moved during the advance movement of the carriage while the carriage is returned by the motor; substantially as described.
16. In a carriage-return mechanism, the combination of a typewriter having a car-
80 riage, a motor for returning the carriage, a variable resistance for regulating the motor circuit, a contact member for the resistance, means for automatically positioning the contact member with respect to the resistance during the advance movement of the carriage and means for retaining the contact member in position during the return move-
85 ment of the carriage; substantially as described.
17. In a carriage-return mechanism, the combination of a typewriter having a car-
90 riage, a motor for returning the carriage, a variable resistance for regulating the motor circuit, means actuated automatically during the advance movement of the carriage for selecting an amount of said resistance depending on the extent of the advance
95 movement of the carriage and means for connecting that amount of resistance in the motor circuit during a portion of the return move-
100 ment of the carriage effected by the motor; substantially as described.
18. In a carriage-return mechanism, the combination of a typewriter having a car-
105 riage, a motor for returning the carriage, a variable resistance for regulating the motor circuit, means actuated automatically during the latter part of the advance movement of the carriage for positioning a contact with respect to the resistance, and means for retaining the contact in position during the return movement of the carriage; substan-
110 tially as described.
19. In a carriage-return mechanism, the combination of a typewriter having a car-
115 riage, a motor connected to the carriage, a member reciprocated in accordance with the movements of the carriage, means operated by said member for reducing the effective power of the motor during the latter portion of the return movement, and means controlled by the extent of the advance
120 movement of the carriage; substantially as described.

movement of the carriage for determining the amount of said reduction; substantially as described.

20. In a carriage-return mechanism, the combination of a typewriter having a carriage, a motor connected to the carriage, a member reciprocated in accordance with the movements of the carriage, means operated by said member for reducing the effective power of the motor during the latter portion of the return movement, a second member positioned by the extent of the advance movement of the carriage and controlling the amount of said reduction and means for retaining said second member in position throughout the return movement of the carriage; substantially as described.

21. In a carriage-return mechanism, the combination of a typewriter having a carriage, a motor, a connection from the motor to the carriage, a tension regulator for the connection, a resistance for the motor circuit, and a contact member for the resistance connected to the motor and operated thereby during the movement of the carriage effected by the motor; substantially as described.

22. In a carriage-return mechanism, the combination of a typewriter having a carriage, a motor, a connection from the motor to the carriage, a tension regulator for the connection, a resistance for the motor circuit, a contact member connected to the motor and operated thereby for connecting the resistance in circuit, a second contact member positioned by said member and controlling the amount of the resistance connected in circuit by the first member, and means for returning the second member to normal position independently of the motor and the first member; substantially as described.

23. In a carriage-return mechanism, a typewriter, a carriage therefor, a platen on the carriage, a lever mounted on the carriage and connected to the platen for actuating the carriage and platen, a bar connected to said lever and mounted on the carriage so as to be movable longitudinally relatively to the carriage, a motor, and a flexible connection from the motor to said bar; substantially as described.

24. In a carriage-return mechanism, a typewriter, a carriage, a platen, a lever mounted on the carriage at one side of the typewriter and connected to the platen for actuating the platen and carriage, a motor mounted on the same side of the typewriter as said lever, a movable bar connected to said lever and extending therefrom in a direction away from the motor, means for guiding the bar as it is moved and a flexible connection from the motor to said base; substantially as described.

25. In a carriage-return mechanism, a typewriter, a carriage therefor, a rotatable

platen on the carriage, a lever mounted on the carriage and connected to the platen for rotating the platen to effect line spacing and for moving the carriage, a bar connected to the lever, said bar being movable independently of the carriage to operate the lever and movable with the carriage during the return movement of the carriage, a motor, and a flexible connection from the motor to said bar; substantially as described.

26. In a carriage-return mechanism, a typewriter, a carriage therefor, a platen mounted on the carriage, line-spacing mechanism mounted at the right hand end of the platen and including a line-spacing lever, a horizontal bar connected to said lever and extending to the left therefrom, means for supporting and guiding said bar, a motor, and a flexible connection from the motor to said bar whereby horizontal movement of the bar to the right effected by the motor will operate the line-spacing lever and move the carriage to the right; substantially as described.

27. In a carriage-return mechanism, a typewriter, a carriage therefor, a platen on the carriage, line-spacing mechanism located at the right hand end of the platen and including a spacing lever for effecting line-spacing manually, a movable bar pivotally connected at one end to the line-spacing lever, means for supporting and guiding said bar so that it lies practically parallel with the platen and extends along the front of the carriage, a motor for returning the carriage, and a flexible connection from the motor to said bar whereby the operation of the motor will effect line-spacing and also move the carriage upon the typewriter frame; substantially as described.

28. In a carriage-return mechanism for typewriters, a carriage and a motor for returning the carriage in combination with a rheostat having a plurality of contacts and means for introducing into the motor circuit resistance proportioned to the length of the return movement of the carriage; substantially as described.

29. In a carriage-return mechanism for typewriters, a carriage and a motor for returning the carriage in combination with a rheostat having a movable member, means for introducing into the motor circuit resistance proportioned to the length of the return movement of the carriage, and means for restoring the movable member of the rheostat to its normal position upon completion of the return movement of the carriage; substantially as described.

30. In a carriage-return mechanism for typewriters, a carriage, a motor for returning the carriage, means for causing the motor to initiate the return movement of the carriage with a strong impulse, and means for automatically reducing the effective

power of the motor during the progress of the return movement of the carriage without opening the circuit of the motor; substantially as described.

- 5 31. In a carriage-return mechanism for typewriters, a carriage, a motor for returning the carriage, means for causing the motor to initiate the return movement of the carriage with a strong impulse, and means for 70 automatically reducing the effective power of the motor during the progress of the return movement of the carriage without opening the circuit of the motor, said means including devices for introducing into the motor circuit resistance proportioned to the length of the travel of the carriage whereby full return movement of the carriage is insured by the momentum acquired by the carriage in the first portion of its movement or by the motor operating with reduced power; substantially as described.

20 32. In a carriage-return mechanism for typewriters, the combination of a carriage, a motor, means operated by the motor for returning the carriage, a rheostat controlling the motor circuit, means for setting the movable member of the rheostat automatically during the advance movement of the carriage, and means for holding said movable member in position during the return movement of the carriage; substantially as described.

25 33. In a carriage-return mechanism, the combination of a typewriter having a carriage, a motor, means operated by the motor for returning the carriage, a rheostat controlling the motor circuit, means for setting the rheostat controlling the motor circuit, means for setting the rheostat automatically 100 to correspond to the length of the printed line, means operated by the return movement of the carriage to cut out the resistance of the rheostat during the first portion of the return movement, and means for including said resistance in the motor circuit during the latter part of the return movement; substantially as described.

30 34. In a carriage-return mechanism, the combination of a typewriter having a carriage, a motor, means operated by the motor for returning the carriage, a rheostat having a movable member controlling the resistance of the motor circuit, means operated by the motor for automatically positioning said movable member during the writing of a line of print, means for holding said member in the position to which it is moved during the return movement of the carriage, and means for automatically restoring said member to its initial position on the completion of the return movement; substantially as described.

35 35. In a carriage-return mechanism, the combination of a typewriter having a carriage, a motor, means operated by the motor

for returning the carriage, a rheostat having a movable member adapted to control the resistance of the motor circuit, means operated automatically by the advance movement of the carriage for cutting in 70 resistance proportioned to the length of the advance movement, means for retaining the movable member of the rheostat in the position in which it has thus been set, means for cutting out the resistance during the 75 first portion of the return movement of the carriage, means for automatically including the resistance in the motor circuit during the latter part of the return movement, and means for restoring the movable member of 80 the rheostat to its normal position on the completion of the return movement; substantially as described.

36. In a carriage-return mechanism, the combination of a typewriter having a carriage, a motor for returning the carriage, means for causing the motor to impart a strong initial impulse to the carriage, and means for automatically inserting resistance into the motor circuit during the progress 90 of the return movement of the carriage; substantially as described.

37. In a carriage-return mechanism, the combination of a typewriter having a carriage, an electric motor for returning the carriage, means for causing the motor to impart a strong initial impulse to the carriage, means for causing the motor to continue said impulse during a portion of the return movement, and means for automatically inserting resistance into the motor circuit at a predetermined point during the 100 progress of the return movement of the carriage; substantially as described.

38. In a carriage-return mechanism, the combination of a typewriter having a carriage, an electric motor for returning the carriage, means for causing the motor to impart a strong initial impulse to the carriage, and means for automatically inserting resistance into the motor circuit during the progress of the return movement, said resistance being automatically proportioned to the distance to be traveled by the carriage in its return movement; substantially as de- 115 scribed.

39. In a carriage-return mechanism, the combination of a typewriter having a carriage, an electric motor for returning the carriage, means for causing the motor to 120 impart a strong impulse to the carriage at the beginning of the return movement, means for continuing said impulse during a portion of the return movement, means for automatically inserting resistance into 125 the motor circuit during the progress of the return movement, and means operated automatically for cutting out said resistance on the completion of the return movement of the carriage; substantially as described. 130

40. In a carriage-return mechanism, the combination of a typewriter having a carriage, an electric motor for returning the carriage, means for automatically inserting 5 a graduated resistance into the motor circuit, said resistance being proportioned to the travel of the carriage during the return movement, and means operated automatically for cutting out said resistance on

the completion of the return movement; 10 substantially as described.

In testimony whereof I affix my signature in presence of two witnesses.

NEAL LARKIN ANDERSON.

Witnesses:

GEO. W. COON,
THOS. MASTIN.

Correction in Letters Patent No. 1,187,124.

It is hereby certified that in Letters Patent No. 1,187,124, granted June 13, 1916, upon the application of Neal Larkin Anderson, of Winston-Salem, North Carolina, for an improvement in "Type-Writer Carriage-Return Mechanism," an error appears in the printed specification requiring correction as follows: Page 8, lines 38-39, claim 33, strike out the words "controlling the motor circuit, means for setting the rheostat"; and that the said Letters Patent should be read with this correction therein that the same may conform to the record of the case in the Patent Office.

Signed and sealed this 25th day of July, A. D., 1916.

[SEAL.]

F. W. H. CLAY,

Acting Commissioner of Patents.

Cl. 197—66.
